WELT TEMPERING MACHINE

Andrew Eppler, Lynn, Mass., assignor to United
Shoe Machinery Corporation, Paterson, N. J.,
a corporation of New Jersey

Application February 26, 1934, Serial No. 712,888

5 Claims. (Cl. 91—41)

The present invention relates to machines for applying moisture to welt employed in the manufacture of shoes.

According to previous practice, machines for moistening welt are provided with a moistening tank and a guide located at or below the level of the water or other liquid in the tank for insuring that the welt is brought into direct contact with the water to moisten the welt to the desired extent. Such an arrangement tends to moisten different parts of the welt unequally, particularly when any portion is left submerged in the water for a long period of time. Due to the nature of welt sewing operations, the welt is not drawn continuously, so that between operations when a portion of the welt is left stationary in the water tank, a much larger supply of water is absorbed. The welt is thereby softened or caused to swell in an irregular manner, resulting in difficult sewing and imperfect work.

The objects of the present invention are to provide a novel and improved welt tempering machine in which limited quantities of liquid are applied to the welt in such a way that even though the welt is held stationary for an indefinite time, no more than the desired quantity of liquid will be applied to the welt.

With these and other objects in view, the present invention contemplates the provision in a welt tempering machine having a tank containing a moistening liquid and guides out of contact with the liquid for directing the welt above the liquid, of means for raising a limited supply of the liquid above the level in the tank and rubbing it directly against one side of the welt throughout that portion of the welt intended to be moistened.

Other features of the invention consist of certain constructions, arrangements and combinations of parts hereinafter described and claimed, the advantages of which will be apparent to those skilled in the art from the following description.

In the drawing, Fig. 1 is a view in side elevation and partly in section of the machine embodying the features of the invention; Fig. 2 is a view in front elevation of the machine, partly in section, and broken away; Fig. 3 is a sectional view taken along the line 3—3 of Fig. 1; and Fig. 4 is another sectional view of certain parts of the machine taken along the line 4—4 of Fig. 1.

In the illustrated machine, the welt extends from any suitable source of supply, over a guide roll 10, through the machine, around a second guide roll 12, and upwardly to the sewing or

other machine with which the welt is to be employed. As the welt, illustrated at 14, is drawn upwardly, it is carried through the illustrated machine and the proper temper imparted.

The welt strip is not submerged or brought into direct engagement with the moistening liquid, but is conducted in a substantially horizontal direction from the guide roll 10, around the major part of a guide wheel 16, to the guide roll 12. Beneath the guide wheel 16 there is provided a tank 18 in which is retained a supply of water. The water supply is kept at a substantially uniform level 20 by means of an inverted bottle 22 in which sufficient water is contained to supply the tank 18, and the tank is shaped with an annular shelf 24 for supporting the bottle in inverted position.

The tank is secured to the frame of the sewing or other machine and carries a supporting bracket 26 for the rolls 10, 12 and 16, secured to the tank by one or more bolts 28 threaded into a thickened portion formed on one side of the tank. The bracket is so located that the wheel 16 is always above the level 20 of the water in the tank, thus preventing direct contact of the welt carried by the roll with the water or the wheel 16 from carrying water to the welt.

In order to raise limited quantities of water from the level 20 to the lower surface of the welt strip 14, there is provided in the illustrated embodiment of the invention a circular bristle brush 30 fixed to one end of a horizontal shaft 32 rotatably mounted in the lower end of a double framed lever 34, the arrangement being such that the major portion of the brush is submerged below the water level in the tank. The lever 34 is fulcrumed on a stud 36 secured by a set screw 37 in a block 38 mounted on the front side of the water tank 18. When the welt is withdrawn from the machine, rotation imparted to the guide wheel 16 causes the brush 30 to rotate and apply the water adhering to the bristles which project above the water level continuously to the lower surface of the welt with a rubbing action.

The shaft 32, on which the circular brush 30 is mounted, is rotated by a gear 40 fixed to the shaft, an idler gear 42 rotatably mounted at one end of the stud 36 on which the lever 34 is fulcrumed, and a gear wheel 44 secured to one end of a shaft 46 rotatable in the bracket 26. The guide wheel 16 is secured to the other end of the shaft 46, thus preventing displacement of the shaft from its bearing in the bracket 26. The gearing between the shafts 32 and 46 acts when the guide wheel 16 is rotated to move the pe-

- riperipheral portion of the brush 30 in the opposite direction with a rubbing action against the welt, and at a higher speed than the speed of movement of the welt strip 14 on the guide wheel 16. 5 The brush 30, being substantially below the water level and rotated faster at its periphery than the welt strip, causes the water to be raised quickly when the movement of the welt strip starts, so that every portion of the welt will 10 have an even application of water.

The water applied to the welt is governed by the amount which adheres to the bristles of the brush 30, the pressure with which the brush engages the welt, and the extent of area of 15 the welt strip covered by the brush. When movements of the welt and brush 30 stop, the water that is already applied to the welt is absorbed and the remainder flows downwardly along the bristles to the level 20 of the water, so that regardless of how long the welt remains stationary, 20 no water will be absorbed more than that which was originally applied to the welt. When the welt is again withdrawn, a further supply of water is raised from the level 20 and applied to 25 an area of the welt overlapping that already moistened on account of rotating the brush 30 faster than the wheel 16, thus ensuring that the proper minimum supply of water will be furnished throughout the length of the welt. 30 To provide a uniform predetermined pressure of the brush 30 against the welt, the brush may be moved towards and from engagement with that portion of the welt which is carried by the lowermost part of the guide wheel 16. The 35 shaft 32 on which the wheel 30 is mounted is raised and lowered by rotating the lever 34 about the stud 36. To regulate the degree of pressure of the brush 30, the upper end of the lever 34 is slotted and surrounds a pin 48 secured at its 40 lower end to the block 38 on which the lever fulcrums. The pin 48 carries a pair of springs 50, one above and one below the slotted upper end of the lever 34, and these springs may be compressed as desired by a thumb nut 52 threaded 45 on the upper end of the pin. By screwing down the thumb nut 52, the pressure of the brush 30 against the welt may be increased to the desired amount.

Preferably, the welt 14 is so threaded through 50 the machine, that the brush will engage the groove, indicated at 54, ordinarily provided in the flesh surface of the welt. The brush may be made to engage the entire flesh surface of the welt or only a small area surrounding the groove 55 54. To regulate the extent of welt area engaged by the brush, the block 38 supporting the lever 34 may be shifted laterally of the welt. For this purpose the block 38 is suitably formed to surround the upper edge of the tank and a thumb screw 56 is provided having a threaded engagement with the block to be clamped against the edge of the tank.

The welt is caused to occupy a predetermined 60 position on the guide wheel 16 by providing a radial flange portion 58 on one side of the wheel, and correspondingly shaped flange portions 60 65 on the guide rolls 10 and 12 to engage the welt along the edge opposite that engaged by the flange 58 on the guide wheel 16. When different widths of welt are employed, the guide rolls 10 and 12 may be shifted in the direction of their axes by rotation of a hand wheel 62 on the opposite side of the bracket 26 from the rolls 10 and 12. The guide rolls are supported on a U-shaped 70 75 member 64, the parallel portions of which pass

horizontally through spaced openings in the bracket and are formed at their ends with journals for the guide rolls 10 and 12. The guide rolls are secured against axial movement at the ends of the U-shaped member by shoulders 5 formed on the member and by nuts 66 at the extreme ends of the member. Rotating the hand wheel 62 produces relative movement between the bracket 26 and the U-shaped member through a shaft 68 on which the hand wheel is mounted having a screw threaded engagement with the bracket 26. The shaft 68 also passes through an opening in the central part of the U-shaped member 64, and causes the member to be shifted when the shaft is rotated by the engagement of a collar 70 at one side and of the hand wheel 62 at the other side of the member. 15

Having thus described an embodiment of the invention, what is claimed is:

1. A welt tempering machine having, in combination, a tank for holding liquid below a predetermined level, a rotatable wheel located entirely out of contact with the liquid in the tank for guiding by engagement with one side only a strip of welt above the liquid level, a shaft, a 25 rotary brush on the shaft having a substantial portion of its periphery submerged in the liquid and arranged to engage that portion of the welt carried by the guide wheel, and gearing between the guide wheel and the brush for rotating continuously the brush at a peripheral speed higher than that of the welt on the guide wheel as the welt is withdrawn.

2. A welt tempering machine having, in combination, a tank for holding liquid below a predetermined level, a rotatable wheel located entirely out of contact with the liquid in the tank for guiding, by engagement with one side only, a strip of welt above the liquid level, a shaft, a rotary brush on the shaft having a substantial portion of its periphery submerged in the liquid and arranged to engage that portion of the welt carried by the guide wheel, gearing comprising an intermediate idler between the guide wheel and the brush for rotating the peripheral portion 45 of the brush with a continuous rubbing action against the welt as the welt is withdrawn, and a lever fulcrumed concentrically with the idler for supporting the brush shaft to permit adjustment of brush pressure against the welt carried 50 by the guide wheel.

3. A welt tempering machine having, in combination, a tank for holding liquid below a predetermined level, a rotatable wheel located entirely out of contact with the liquid in the tank for guiding by engagement with one side only, a strip of welt above the liquid level, a shaft, a rotary brush on the shaft having a substantial portion of its periphery submerged in the liquid and arranged to engage that portion of the welt carried by the guide wheel, gearing for rotating the brush only as the welt is withdrawn, a lever on which the brush shaft is supported, and adjustable means for mounting the lever on the machine to permit different amounts of the welt 65 surface to be engaged by the brush.

4. A welt tempering machine having, in combination, a tank for holding liquid at a predetermined level, a rotatable wheel formed with a flange for guiding one edge of a welt strip in 70 engagement with the wheel, a brush actuated from the guide wheel as the welt is withdrawn for applying a limited quantity of the liquid with a continuous rubbing action against one side of the welt along the portion engaged by the guide 75

wheel, additional guiding means adjustable towards and from the other edge of the welt before and after it is carried to the guiding wheel for preventing displacement of the first welt edge 5 from the flange on the wheel, and a single regulating means for changing the positions of the guiding means transversely of the welt.

10 5. A welt tempering machine having, in combination, a tank for holding liquid at predetermined level, a rotatable wheel formed with a flange for guiding one edge of a welt strip in engagement with the wheel, a brush actuated

from the guide wheel as the welt is withdrawn for applying a limited quantity of the liquid with a continuous rubbing action against one side of the welt along the portion engaged by the guide wheel, guide rolls having flanges engaging the other edge of the welt before and after it is carried to the guiding wheel to prevent displacement of said first edge of the welt from the flange on said wheel and a single regulating device for simultaneously changing the positions of the 10 guide rolls transversely of the welt.
